TRUSS OR BRIDGE

Thomas Maddock, Phoenix, Ariz.

Application January 27, 1930, Serial No. 423,772

4 Claims. (Cl. 14—16)

The invention relates to a new and useful arrangement of the members of trusses or bridges which will provide for their expansion and contraction while retaining their continuity and rigidity.

The object of the improvement is to reduce the amount of materials and cost of trusses and bridges.

Expansion and contraction are to be provided for within a simple truss, or within or between multiple trusses and girders of all types and sizes in order to reduce secondary stresses; to reduce the lateral thrust on columns and piers; to utilize the economic advantage of continuous trusses and girders without being limited in their length by the movement due to expansion or contraction from heat or stress variation; to increase the rigidity and strength of cantilever truss and girder connections with suspended spans; to increase resistance to wind stresses and to decrease the amount of false work required in erecting trusses.

The expanding truss is illustrated by the accompanying drawing.

Figure 1 is a side elevation of a ten panel truss embodying one form of an expanding panel.

Figure 2 is a side elevation of two seven panel trusses with a supported expanding connection between the trusses.

Figure 3 is an enlarged side elevation of the expanding panel shown in Figure 1.

Figure 4 is an enlarged side elevation of the expanding connection shown in Figure 2.

Figure 5 is a side elevation of a variation of the type of expanding panel shown in Figure 1.

The side elevation shown in Figure 1 includes a truss and part of the adjoining continuous trusses. The central span of the truss is suspended by the cantilever arms at 8 and 10.

The suspended span is connected to the right hand cantilever arm by an expanding panel shown enlarged in Figure 3.

The crossed members 2—9 and 3—8 are provided at their approximate center with a pin (6) to enable them to move and permit an approximately equal variation in the horizontal distance between the ends of the cross 2 and 3, and 8 and 9 in accordance with the expansion and contraction in the truss.

Ends of the members 1—2, 3—4, 2—9 and 3—8 are provided with pin connected joints. The other joints in the truss may be riveted.

The crossed member 2—9 is itself trussed by the members 2—7, 7—9 and 6—7 to resist bend-

ing moments. The member 3—8 is similarly trussed.

The expansion panel should be located where the shear stresses of the suspended span and the tension and compression stresses in the top and bottom chords will result in a minimum of bending moments in the crossed members 2—9, 3—8, etc.

The truss may be attached to the piers 20 and 21 by rigid shoes unless it is desired to have this span provide expansion for the adjoining spans, in which case, roller bearing, rocker arms or similar arrangement for permitting longitudinal movement are necessary for the pier bearings.

The side elevation of the two trusses shown in Figure 2 include parts of the adjoining continuous trusses.

The two trusses are connected over the pier 23 by crossed members forming an expansion connection or tower which is shown in detail in Figure 4.

Movable joints or pin connections are provided at the ends of the members 11—12, 13—14, 12—19 and 13—18.

The movable arm 12—19 is itself trussed by the members 12—17, 17—19 and 16—17 to resist bending moments. The member 13—18 is similarly trussed.

The pin at 16 is located so as to provide practically equal horizontal movement at 11 and 18, 30 and 14 and 19.

Bearing plates are provided with rollers to permit longitudinal movement on pier 23. Rockers may also be used.

The trusses can be rigidly attached to piers 22 and 24 unless it is desired to provide for the expansion of more than two trusses at pier 23.

The side elevation of an expanding connection shown in Figure 5 is similar to that in Figure 1 except that it does not add to the length of the bridge, but merely provides that the usual hanger 3—8 which connects the cantilever arm with the suspended span is made one of the crossed members.

In operation of the crossed members shown in Figure 1, as expansion moves pin 8 toward pin 9 pin 6 will be raised approximately half as much while pins 2 and 3 will have a vertical movement approximately equal to the horizontal movement between 8 and 9. This vertical movement at 2 and 3 results in a small additional horizontal movement which tends to vary the distance from 2 to 3 with that from 8 to 9. This variation must be kept small. As the angle 2—6—3 of the cross members as constructed is decreased this varia-

tion approaches zero. Thus the more expansion to be taken care of in the trusses the less must be the angle 2—6—3. The same is true of Figure 2 where the inclination of the members 11—12 and 13—14 add to the variation.

5. The pin at 6 in Figure 1 can be located off center to partially correct variable horizontal movements between 2 and 3, and 8 and 9. The pin at 16 can be similarly located.

10. Figure 5 is an illustration of an expanding connection that will have a minimum vertical movement in pins 6—2—8 and 9.

I am aware that methods have long been employed to permit expansion and contraction at the ends of trusses, also that simple hanger connections allow for the same, between cantilever arms and suspended spans, but these do not permit of continuity in a structure.

I claim:

20. 1. A continuous truss construction having an expanding and contracting panel consisting of crossed members, pin connected at their approximate center with two of the four ends of the crossed members directly pin connected to the chords and the other two ends pin connected to struts or ties with the other end of such struts or ties pin connected to diagonally opposite chord points, the entire panel and its connections permitting the ends of the truss to be fixed to their supports by providing internally in the truss for longitudinal variations in length due to temperature changes and stresses.

25. 2. A connection or tower between trusses con-

sisting of diagonally crossed members supported by single or double pliers, pin connected at their approximate center, with their bases pin connected to the ends of the lower chords of the trusses and their apices pin connected to tension members which are in turn pin connected to the ends of the upper chords, the entire tower and its connections securing continuity between the adjacent trusses without interference with the longitudinal movement of the ends of the trusses produced by stresses and temperature changes.

3. A connection between cantilever arms and suspended spans consisting of diagonally crossed members pin connected at their approximate centers with one of the crossed members pin connected to the cantilever arm and suspended span similar to the usual hanger and the other crossed member pin connected at its base to a strut in turn pin connected to the lower chord of the cantilever arm and pin connected at its apex to a tie 20 to the opposite end of which is in turn pin connected to the upper chord of the suspended span.

4. A continuous span construction having an expanding and contracting panel consisting of two members connected at their approximate center with each member connected to diagonally opposite chord points, two of the end connections being made directly to the chords and the other two connections being made to strut-ties in turn connected to the chords; all the members being 25 free to rotate at their connections.

THOMAS MADDOCK.
